(57) **CLAIM**

I claim the ornamental design for a comb cutter, as shown.

DESCRIPTION

FIG. 1 is a perspective view of an embodiment of a comb cutter embodying my new design showing a left, front and top view thereof;

FIG. 2 is a right side elevational view thereof;

FIG. 3 is a top plan view thereof;

FIG. 4 is a left side elevational view thereof;

FIG. 5 is a bottom plan view thereof;

FIG. 6 is a front elevation view thereof; and,

FIG. 7 is a rear elevation view thereof.
